DESIGN FOR A GRID BLOCK FOR A METAL TREATMENT TROUGH

Frank J. Wood, Riverside, Ill., assignor to Goodman Manufacturing Company, Chicago, Ill., a corporation of Illinois

Application May 15, 1944, Serial No. 113,599

Term of patent 7 years

(Cl. D54—1)

To all whom it may concern:

Be it known that I, Frank J. Wood, a citizen of the United States, residing in Riverside, in the county of Cook and State of Illinois, have invented a new, original, and ornamental Design for a Grid Block for a Metal Treatment Trough, of which the following is a specification, reference being had to the accompanying drawing, forming a part thereof, wherein:

Figure 1 is a perspective view of a grid block

for a metal treatment trough, constructed in accordance with my invention;

Figure 2 is a view in side elevation of the grid block shown in Figure 1; and

Figure 3 is an end view of the grid block shown in Figure 1.

I claim:

The ornamental design for a grid block for a metal treatment trough, as shown.

FRANK J. WOOD.
